DRILL UNIT

John B. Long, Oak Hill, and Jeff C. Clay, Fayetteville,
W. Va., assignors to The Long Company, Oak Hill,
W. Va., a corporation of West Virginia

Application August 5, 1957, Serial No. 47,229

Term of patent 14 years

(Cl. D54—14)

FIG. 1

FIG. 2

FIG. 3

FIG. 4

Fig. 1 is a perspective view looking downwardly at the front and right side of a drill unit embodying this design.

Fig. 2 is a bottom plan view thereof.

Fig. 3 is a front elevation thereof.

Fig. 4 is a perspective view looking downwardly at the rear and left side thereof.

The essential features of our design reside in those portions shown in full lines.

We claim:

The ornamental design for a drill unit, as shown and described.
